CURTAIN ROD DEVICE

Joseph R. Guildford, Regina, Saskatchewan,
Canada

Application March 14, 1939, Serial No. 261,748

3 Claims. (Cl. 223—105)

My invention relates to improvements in a curtain rod device, and has for its primary object to provide, in a manner as hereinafter set forth, a curtain protector embodying a novel construction through the medium of which, curtains may be threaded on to curtain rods without danger of tearing the curtains.

With my invention, the sharp ends, usually found on the majority of curtain rods, are covered, and the possibility of tearing the curtains in threading them on to the rods is eliminated.

Curtain rods vary somewhat in dimensions, therefore it is necessary to provide means of clamping this curtain rod device to the rod to prevent it from falling off. The means adopted will be readily understood.

The object and advantages of the invention will become apparent from a study of the following specification, taken in conjunction with the accompanying drawing wherein like characters of reference designate corresponding parts throughout the several views, in which—

Figure 1 is a vertical view showing a curtain rod device with the integral spring portion in normal position.

Figure 2 is a vertical end view of Figure 1 on the line 2—2.

Figure 3 is a vertical view showing a curtain rod device in place on a curtain rod.

Figure 4 is a horizontal sectional view of Figure 3 on the line 4—4.

Figure 5 is a vertical end and sectional view of Figure 3 on the line 5—5.

Referring to the drawing:

The numeral 6 represents a sheath or walled casing preferably constructed of Celluloid, open at the end 8 to receive the curtain rod 10 and closed at the opposite end 7.

The numeral 9 represents an integral spring or clamping portion formed in the wall 16 of the casing 6 by cutting or perforating the wall 16 at 12. The numerals 13 are portions of the wall 16 cut out to prevent the rupturing of the wall 16 beyond these points.

When the device is placed upon a curtain rod the integral spring 9 is pressed inward by the thumb or forefinger and as the end 11 of the rod enters the device at 8 the portion 15 of the end 11 enters between the wall 16 and the spring portion at 14. As the rod 10 continues its entrance into the device the tighter the spring will grip thereby preventing the device from falling off.

It will be noted that when the curtain rod enters the device the spring portion at 14 tends to move interiorly in the direction of the imper-

forated wall of the casing 6 until it abuts the said imperforate wall. Then as the rod is inserted further into the device the tension of the spring 9 is increased, greatly enhancing the clamping effect of the device on to the rod.

5

I claim:

1. A curtain rod device comprising a casing for enclosing the end of a curtain rod, said device being provided with an integral resilient portion for clamping said device to said curtain rod, said casing being closed at one end and open at its opposite end and provided with comparatively flat front and rear walls, said open end provided for the insertion of said rod, said integral resilient portion formed tongue-like by perforating one of the said flat walls intermediate of the open and closed ends of said casing and normally retained in alignment with said perforated wall while in a state of inertia, the remaining flat wall of the casing forming an abutment limiting the movement of the end of said resilient portion as it is moved inwardly of the casing, said resilient portion having its free end extending in the direction of said open end of the casing and adapted to clamp the wall of said rod between said resilient portion and the perforated wall of said casing.

2. A curtain rod device comprising a casing for enveloping the end of a curtain rod, said device being provided with an integral resilient portion for clamping said device to said curtain rod, tightening means to increase the tension of said clamping means, said casing being closed at one end and open at its opposite end and provided with comparatively flat front and rear walls, said open end provided for the insertion of said rod, said integral resilient portion formed tongue-like by perforating one of the said flat walls intermediate of the open and closed ends of said casing, said tongue-like portion having its free end extending in the direction of the open end of said casing and adapted to clamp the wall of said rod between said tongue and the perforated wall of said casing, said tightening means being provided by the remaining flat wall of the casing forming an abutment limiting the movement of the free end of said tongue, said limited movement causing increased tension to the resilient tongue-like portion as the rod enters the casing.

45

3. A curtain rod device for enveloping the end of a curtain rod to prevent the tearing of curtains comprising a receptacle having integral clasping means, said receptacle consisting of a jointless sheath having a closed end and an open

50

55

end, said open end being provided for the insertion of the end of a curtain rod, said integral clasping means formed by perforating a wall within the limits of the receptacle to provide a tongue, the free end of said tongue extending in the direction of the said open end of the re-

ceptacle and adapted to enter the interior of said curtain rod causing the wall of said rod to be held fast between said tongue and said perforated wall.

JOSEPH R. GUILDFORD. 5
